[57] **CLAIM**

The ornamental design for combined adjustable lamp and reflector for photographic lighting or the like, as shown and described.

DESCRIPTION

FIG. 1 is a front elevational view of combined adjustable lamp and reflector for photographic lighting or the like showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view thereof with the adjustable light and reflector in alternate positions.

The stand is broken away in the elevational views to indicate indeterminate length.

FIG. 1

FIG. 2

FIG. 3

FIG. 4

FIG. 5

FIG. 6

FIG. 7
